COMPOUND ABRADING AND BRAZING
MACHINE

Leighton A. Wilkie, Glencoe, Ill., assignor to Continental Machines, Incorporated, Minneapolis, Minn., a corporation of Minnesota

Application May 27, 1935, Serial No. 23,554

12 Claims.

(Cl. 29—68)

The invention relates to cutting and abrading tools of the endless band type and means for maintaining the band in operative condition.

One of the objects of the invention is the provision of new and improved mechanism for abrading which is provided with novel means for maintaining the abrading elements in alignment during their operation.

Another object of the invention is the provision of new and improved abrading mechanism as an article of manufacture having means mounted on the support for said mechanism for readily uniting the band portions in the event of breakage or fracture.

15 A further object of the invention is the provision of new and improved mechanism for connecting ends of a broken or severed band together in such manner that the connected portion will have substantially the same cross sectional area as the remaining portion and will be 20 equally as strong.

25 A further object of the invention is the provision of new and improved compound abrading and brazing machines which are simple in construction, easily operated and efficient.

Other and further objects and advantages will become apparent as the disclosure proceeds and the description is read in conjunction with the accompanying drawings, in which—

30 Fig. 1 is a perspective view of the apparatus; Fig. 2 is a side elevation of a portion of the band holding member;

Fig. 3 is a section on the line 3—3 of Fig. 5;

Fig. 4 is a section on the line 4—4 of Fig. 1;

35 Fig. 5 is a front elevation of the device shown in Fig. 3 with parts in section and parts broken away;

Fig. 6 is a front elevation of the band holding device with parts broken away;

40 Fig. 7 is a side elevation of the abrading machine with parts broken away;

Fig. 8 is a front elevation of the apparatus shown in Fig. 7 on an enlarged scale with parts in section and parts broken away;

45 Fig. 9 is a section on the line 9—9 of Fig. 8;

Fig. 10 is a section on the line 10—10 of Fig. 8;

Fig. 11 is a perspective view of the guiding means and the abrading mechanism showing the parts disassembled;

50 Fig. 12 is a perspective view of a pair of the abrasive elements showing the parts detached from their support, but illustrating them in interlocked position; and

55 Fig. 13 is a section on the line 13—13 of Fig. 8. In certain types of work, it is necessary to

drill a hole in the same, insert the saw and enlarge the opening; then rout out or further enlarge the opening by filing and finally finishing the work by honing the edges of the opening. The present apparatus has for its principal object the provision of means whereby all or part of these operations may be mechanically accomplished inexpensively and expeditiously on a single machine. Under such circumstances, the band must be non-continuous or must be 10 severed or broken, and after insertion in the opening the ends connected together. In the filing or honing operation, the bands are provided with detachable ends, but in the sawing operation, since the band must be continuous 15 and of uniform thickness, it becomes necessary to weld or braze the ends together.

Furthermore, in the use of band saws, especially of the smaller type, it is not uncommon for the band to break and require repairing by 20 welding or brazing. Usually separate welding machines are required for joining the ends of the bands and more often than otherwise the band must be sent elsewhere, or, at least, carried to another part of the plant to be welded 25 or brazed. In any event, valuable time may be lost and considerable unnecessary expense involved in having the ends of the band connected together.

The present invention seeks to avoid this difficulty by the provision of a combined sawing, abrading and honing machine and a welding or brazing apparatus. The present device comprises a sawing or abrading apparatus and a repair device so constructed that the whole constitutes a unitary device as a single article of manufacture.

Referring now to the drawings, the reference character 10 designates a combined sawing and abrading apparatus which comprises a base 11, an abrading or sawing mechanism 12 mounted on the base 11, a clamping and welding device 13 mounted on the base and a band holding device 14. The base 11 is a hollow structure, the upper surface of which is stepped having an upper horizontal portion 15 on which is mounted the abrading mechanism 12 and a lower horizontal portion 16 on which the devices 13 and 14 are mounted. The operating mechanism for the abrading device is substantially the same as that of a conventional band saw and comprises a support 17 in the lower portion of which is journaled a lower pulley 18 and in the upper portion of which is journaled an upper pulley 19.

The bearing 21 for the upper pulley 19 is ver-

tically adjustable as at 22, as shown in dotted lines in Fig. 1, for varying the distance between the pulleys for adjusting the tension of the band, as is usual in such constructions. The lower 5 pulley 18 is rotated by a motor in the usual manner for operating an endless band 23 trained about the pulleys 18 and 19. This band 23 may have one edge serrated for constituting a band saw.

10 The apparatus is provided above the pulley 18 with a rest or table 24 for supporting the work, while it is being operated upon, and guiding mechanism 30 for the band above the table, as is usual in such constructions.

15 Since the details of the structure thus far described may be the conventional band saw construction, it is not thought necessary to further illustrate or describe the same.

20 When the apparatus is to be used as an abrading or honing device, the band saw 23 is removed and a flexible steel band 25 (see Figs. 7 to 12), having the abrading elements 26 rigidly attached thereto, is substituted therefor.

25 The abrading elements may be in the form of files, hones or the like, depending upon the work to be done, and each is rigidly attached to the band 25 at their intermediate portions, as by means of rivets or the like 27. These rivets are arranged in a plane transversely to the band 30 whereby they will not interfere with the bending of the band, as it passes around the pulleys 18 and 19.

35 Each of the abrading elements 26 has a V-shaped recess 28 in one end and a corresponding V-shaped projection 29 on the other, as clearly shown in Figs. 8, 11 and 12. The abrading elements are so arranged on the band that the V-shaped projection 29 on one end will engage in the V-shaped recess in the adjacent end 40 of an adjacent element during the straight run of the belt, whereby, during the operation of the device, the abrading elements will be held in alignment parallel with the band.

45 By dovetailing the ends of the abrading elements, these elements will not only be held in alignment, but, the meeting lines or edges of the joints being arranged at an angle to the direction of travel of the belt, there will be a gradual transition from one element to another 50 as they engage the work during the travel of the belt. This is considered an important feature of the invention because it not only adds to smoothness of performance, but lends itself to accuracy in the operation of the device.

55 In order to facilitate the attachment and removal of the band 25 from the pulleys 18 and 19, the band is split and the ends are provided with a pin and slot connection, as shown in Fig. 11. One end of the band is provided with a headed 60 stud 31 which is rigidly connected to the band and the other is provided with a keyhole slot 32 for engaging the stud.

65 The two abrading elements on the ends of the band may have their abutting ends provided with a recess 30 for receiving the head 31 of the unit. In other words, the recesses provide a clearance for the head 31 of the band during the operation of the device.

70 In removing the band, the bearing 21 is adjusted downwardly sufficiently to enable the pin to be moved to the enlarged portion of the slot 32, after which the ends may be separated.

75 By providing a split band with means for detachably connecting the ends together, the band may be readily positioned in a closed opening for

enlarging the same and the like. This is considered an important feature of the invention since it permits the use of a steel band and at the same time obviates the necessity for cutting or breaking the band and welding or brazing the 5 ends when it is desired to rout out or enlarge an opening. The apparatus may be provided with a band saw, a band having filing elements thereon and a band having honing elements thereon whereby all three operations may be performed 10 successively on the work, if desired, with but little expenditure of time in changing the bands. For instance, the time required for welding and applying the saw band is approximately one to two minutes and the other bands may be changed in 15 about the same time.

Suitable means are provided for preventing bending of the abrading device while it is passing the rest or table 24 when pressure is applied to it during its operation. In the form of the 20 device selected to illustrate one embodiment of the invention, a backing or guiding device 33 is employed for this purpose.

This device comprises a channel member 34 to which is rigidly connected an upwardly extending arm 35 (see Fig. 7) which is vertically adjustable through a sleeve 36 of the support 17. The channel member 34 is arranged inwardly of the band 25 and has its flanges extending outwardly. The flanges are provided with rabbets 38 and 39 which form the ledges 41 and 42 on the inner side of the flanges of the channel, as clearly shown in Figs. 9 and 11 of the drawings.

In order that the abrading elements may engage these ledges without wear on the band, the 35 band is narrower than the abrading elements. The band is slightly narrower than the width of the slot at the base of the flanges whereas the abrading elements engage the ledges.

In other words, during the operation of the 40 device, the ledges will constitute backing members for reinforcing the abrading elements 26. The depth of the groove beneath the ledges is such as to provide sufficient clearance for the heads of the rivets 27 and for the inner end of 45 the stud 31.

The channel member 34 extends both above and below the rest or table 24 (see Fig. 8) and the portion of the flanges outwardly of the ledges 41 and 42 are removed for a short distance above 50 the table or rest 24 to provide access to the abrading elements. The width of the channel member 34 at the point where the outer portions of the flanges are removed is reduced to substantially the width of the abrading members 55 (see Fig. 10) whereby free access is had to the abrading elements. The flanges at the upper portion of the flange member 34 and at the upper end of those beneath the table or rest 24 are beveled outwardly, as shown at 43 and 44, 60 for guiding the abrading members between the flanges during the operation of the device.

Suitable means are provided above the table or rest for guiding the band and abrading elements. As shown, a U-shaped guide member 46 65 having the anti-friction rollers 47 mounted therein is employed for this purpose. The guide member has an extended arm 48 (see Figs. 9 and 13) provided with a horizontal slot 49 and said arm is adapted to be adjustably connected to an angle 70 plate 51 rigidly attached to the channel member 34. The plate 51 is provided with a vertical slot 52 through which a clamping bolt 53 extends for adjustably connecting the arm 48 to the plate 51. By means of the slots, the mem- 75

ber 46 may be raised or lowered or adjusted inwardly and outwardly to and from the abrading elements 26. The length of the rollers are substantially the same as the width of the channel member 34 whereby the abrading elements will be held in the channel at a point just above where the flanges are removed, as shown in Fig. 9 of the drawings.

In the operation of band saws and abrading elements employing flexible steel bands, it is at times desirable to insert the band through an opening or sometimes these bands or saws will become broken and it becomes necessary to connect the broken ends.

The apparatus 14 is provided with means for accomplishing this result, thereby reducing the time necessary to repair the band to a minimum. In connecting the ends of steel bands, it is common practice to braze the same. In order that the brazed portion of the band shall be of substantially the same thickness as the remaining portion of the band—which, of course, is absolutely necessary in the case of band saws, and which is also desirable, but not necessary, in bands used in abrading mechanism—the broken ends of the band are tapered or scarfed so that the ends may be overlapped for brazing the same. Since the bands for the abrading elements must have constant lengths, due to the interfitting of these elements, when one of these bands breaks or is severed, an additional piece or length is necessary. The broken ends are spliced to this additional piece. In tapering the broken end of the band, one end portion of the band is secured in the band holding device 14. This device comprises a base or support 54 on the upper portion of which is mounted the form member 55 which has the upper surface of each end beveled or tapered downwardly, as shown at 56 and 57. A clamping member 58 is provided for clamping the end of the band on the form member 55. Then with the aid of a file 59, the upper surface of one end of the band may be filed to a proper taper. If the band is a saw the ends are reversed and the opposite end tapered on the opposite side. After the ends have been tapered, they are brazed in the welding device with brazing material inserted between the overlapping ends.

The brazing or welding apparatus has its two poles 61 and 62 extending above the lower plate 16 of the base 11 of the device and is provided with clamping members 63 and 64, respectively, which is adapted to clamp the ends of the band at opposite sides of the lapped portions for holding them in position to be brazed or welded. The brazing or welding apparatus may be of any suitable construction, that shown comprises the primary winding 65, a laminated core 66 and a U-shaped conductor 67 which may be considered as constituting the secondary winding. Since the details of the winding and construction of this portion of the welding device constitutes no part of the invention, further illustration and description are considered unnecessary.

Suitable means are provided for clamping the overlapped portions of the band during the brazing operation. In the form shown, the clamping member comprises a lever 68, pivoted as at 69, and provided with a clamping jaw 71 pivoted to the lever. An adjustable stud 72 is provided for engaging the lower portion of the clamping jaw 71. The lower portion of this jaw is provided with a cam surface 73 so arranged that when the lever 68 is lowered to bring the contact mem-

ber 74 into contact with the overlapping portions of the band, the engagement of the stud with the cam surface will cause the contacting member 74 of the jaw 71 to contact the under-surface of the overlapping members of the band. After the lever has been lowered for clamping the overlapping ends of the band together, the circuit is closed by the operation of the switch 75 (see Fig. 4).

Preferably a rheostat is connected with the switch 75 so that the desired or required amount of heat may be applied for brazing the overlapped ends of the band. It sometimes happens in the brazing operation the band will be slightly enlarged at the lapped portion and it may be necessary to reduce the thickness of the band at this point.

The mechanism shown in Fig. 6 is employed in reducing the enlarged portion of the band after the brazing operation. For the sake of convenience, the terminals 61 and 62 are utilized for this purpose. The terminals are provided with arms 76 and 77, respectively, which extend in opposite directions and the outer end of each is slotted and provided with a clamping member or screw 78. A strip of flexible material 79 of greater length than the distance between the slots at the ends of the arms 76 and 77 has its ends secured in the slots, thereby forming an arch 81 on which the band has been secured in the position shown in Fig. 6, the enlarged portion may be readily removed by a file or other abrading device.

The table 24 is tiltable in the usual manner whereby the marginal walls of openings may be given the desired bevel.

If during the operation of the sawing or abrading device it becomes necessary or desirable to enlarge an opening having a continuous marginal wall, the band is severed, if it is a band saw, the temper of the severed ends is drawn by heating the same in the brazing device, and after the ends are scarfed they are brazed or welded together and the enlargement, if any, removed by a file in the band holding device 14. The band is then replaced around the pulleys and the device is ready for the sawing operation. In case the abrading band becomes broken the same may be mended by brazing both ends to a connecting strip to maintain the proper length. In the event it is desired to enlarge the opening by abrading the marginal wall thereof, the band is detached by releasing the button and then inserting the same through the opening in the work, and then replacing the band.

It will thus be seen that the apparatus is a self-contained unit capable of being changed from sawing to filing or to a honing device, as occasion may require. The apparatus may be considered as being a convertible device inasmuch as it may be readily changed from one type of operating device to another within a minimum of time and labor. Furthermore, mounting the brazing mechanism on a step lower than that on which the band operating mechanism is mounted places the brazing device in a position where it will not interfere with the operation of the sawing or abrading mechanisms or be interfered with by them.

While the disclosure is by way of example only, it is understood that various changes may be made without departing from the spirit and scope of the invention, as defined in the following claims.

I claim as my invention:

1. A band for an abrading device comprising a flexible band, a headed pin on one end of said band for engaging a keyhole slot in the other end of said band for connecting said ends together, and a plurality of abrading elements secured to said band, the adjacent ends of said elements on the ends of said band being provided with cooperating slots for affording clearance for the head of said pin during the straight run of 10 said belt.
2. In a filing machine, the combination of a frame, a plurality of vertically spaced pulleys supported therefrom, a horizontal table supported from said frame and providing a vertical opening, a carrier guided on said pulleys for movement of a portion downwardly in a straight line path extended through said opening, and file elements fixed on the front of said carrier to provide a substantially continuous front filing surface in said path and defined between two parallel spaced vertical planes, the longitudinal ends of adjacent file elements being provided with mutually interlocking portions closely laterally fitted in a manner preventing relative lateral movement therebetween within said straight line path 20 in directions at right angles to said planes.
3. As an article of manufacture, a base comprising a lower and an upper platform rigidly connected together, sawing mechanism, including an endless saw band mounted on the upper platform, and welding mechanism mounted on the lower platform for uniting the ends of said band when said band is severed.
4. In an abrading device, a pair of pulleys, a working zone between said pulleys, a metallic band trained about said pulleys, means for rotating one of said pulleys, and file elements rigidly connected to said band, the adjacent ends of said file elements interfitting for preventing relative lateral movement of said ends, said band having a continuous filing surface on its front face as it moves across said working zone, and means on the adjacent ends of said band for detachably connecting the same together whereby said band may be inserted in closed openings for filing the interior thereof and for removing the band and said elements from said openings.
5. In an abrading machine, a pair of pulleys spaced vertically, an endless band trained around said pulleys, a plurality of file members, each of said members having a recess in one end and a corresponding projection on the opposite end for engaging said recess for preventing relative lateral movement of said ends, means for rigidly connecting the medial portions of said members to said band, and means for detachably connecting the ends of said band together, said band having a continuous front filing surface.
6. In a convertible band saw and welding device, a hollow base having a stepped upper surface comprising an upper and a lower step, a convertible band saw and filing device mounted on the upper step, and a welding device mounted on the lower step of said base for uniting the ends of the band saw when the same is severed.
7. In a convertible filing and sawing apparatus, a support, a pair of vertically spaced pulleys mounted on said support and adapted to have trained about them a thin steel flexible saw band or a thin steel flexible file band, interchangeable guide and backing members for said bands, respectively, means for detachably connecting said members, one at a time, to said support, said file band being split and having its ends detachably connected together, file elements hav-
- ing interengaging ends, mounted on said file band, and a saw band welding device mounted on said support for connecting the ends of said saw band when the same is severed whereby said apparatus is adapted to perform either sawing 5 or filing on internal surfaces.
8. In an abrading device, a thin flexible band, abrading elements, means for securing an intermediate portion of each element to said band, the adjacent ends of said elements being provided with interlocking portions for preventing relative lateral movement of said ends, said interlocking portions including joints extending at an angle to the direction of travel of said band, said elements when in alignment having a continuous filing surface on their front faces.
9. In an abrading device, a flexible band, abrading elements, means for securing the intermediate portions of said elements to said band, and interlocking connections between the adjacent ends of said elements for preventing relative lateral movement of said ends, said elements forming a continuous filing surface on the face thereof when in alignment.
10. In a device of the class described, a base, a pair of vertically spaced pulleys mounted on said base, a metallic flexible band trained about said pulleys, and abrading elements mounted on said band, said elements having interlocking connections 15 between the adjacent ends of adjacent elements for preventing lateral movement of one of said ends relative to the other, the faces of said elements when interlocked constituting a continuous filing surface, and the line formed by the interlocking connection having portions thereof at an acute angle to the center line of the band.
11. In a device of the class described, a base, a pair of vertically spaced pulleys mounted on said base, a working zone between said pulleys, a metallic flexible band trained about said pulleys, and abrading elements mounted on said band, the ends of said elements lapping past each other, the joint between the ends of adjacent elements 20 extending in a non-straight line across said elements, said elements having a continuous filing surface at said working zone.
12. In a metal filing machine, a file carrier adapted to travel around a pair of circular pulleys spaced apart in a common plane for movement of a portion of said carrier in a straight line path, a plurality of file elements on the outer surface of said carrier to provide substantially a continuous filing surface along said straight portion, rivets through said carrier and elements for securing said elements to said carrier, said rivets being located at points removed from the ends of said elements, whereby when said carrier is in use, the ends of said elements will be 25 spaced from the carrier while passing around the circular pulleys, the adjacent ends of said file elements being provided with mutually interlocking portions closely laterally fitted in a manner for preventing relative lateral movement between said ends within said straight line path in a direction at right angles to the plane of said pulleys, when in use, said carrier being split, means for detachably connecting the ends of said carrier together to form an endless member, whereby said carrier and elements may be inserted through a closed opening for enlarging the same.

LEIGHTON A. WILKIE.

CERTIFICATE OF CORRECTION.

Patent No. 2,180,078.

November 1^h, 1939.

LEIGHTON A. WILKIE.

It is hereby certified that error appears in the printed specification of the above numbered patent requiring correction as follows: Page 4, first column, line 23-24, claim 2, for "fitted" read fitted; same page, second column, line 29, claim 10, strike out the words and comma "said elements mounted on said band,"; and that the said Letters Patent should be read with this correction therein that the same may conform to the record of the case in the Patent Office.

Signed and sealed this 19th day of December, A. D. 1939.

Henry Van Arsdale,

(Seal) Acting Commissioner of Patents.
